UNITED STATES PATENT OFFICE.

JOSEPH ROSMAN, OF NEW YORK, N. Y.

NECKTIE RETAINER.

Application filed March 1, 1928. Serial No. 258,177.

This invention relates to necktie retainers and in particular to a retainer adapted to secure a necktie directly to the front collar button of a shirt.

5 An object of the present invention is to provide a necktie retainer comprising a supplemental head portion on the forward end of a collar button adapted to resiliently engage a co-operating part on the rear face 10 of the necktie.

Another object of the invention is to provide a collar button with spaced flanges separated by a shank of non-circular cross section so that it will be held against angular 15 movement when in position within the buttonholes of the collar band of a shirt, and also to provide interengaging means between the forward end of the collar button and the necktie of non-circular cross section so 20 that the tie will also be held against angular movement relative to the collar button and the collar band.

One feature which enables me to accomplish the above named objects is that the 25 collar button in addition to the usual spaced flanges or heads and a shank portion is provided with a supplemental or additional head closely adjacent and on the front face of the forward flange or head. A neck or shank 30 portion between the supplemental head and the forward flange or head of the collar button being of oval or non-circular contour. Adapted to engage the oval or non-circular contour between the supplemental head and front flange of the collar button is a resilient 35 fastener having portions engaging over the supplemental head.

With the above and other objects in view 40 my invention consists in the features of construction and operation set forth in the following specification and illustrated in the accompanying drawings.

In the accompanying drawing, annexed hereto and forming part of the specification 45 I have shown my invention embodied in a fastener or retainer for a necktie of the bow type, but it will be understood that the invention can be otherwise embodied and that the drawing is not to be construed as defining or 50 limiting the scope of the invention, the claims appended to the specification being relied upon for that purpose.

In the drawing—

55 Fig. 1 is a plan view of the necktie retainer showing it in position retaining the necktie to the collar band of a shirt;

Fig. 2 is a rear view of the necktie with its portion of the retaining device attached thereto;

Fig. 3 is a perspective view of the special 60 form of collar button and necktie retainer forming part of this invention; and

Fig. 4 is a plan view of a slightly modified 65 form of the invention.

In the above mentioned drawing I have 70 shown two embodiments of the invention which are now deemed preferable, but it is understood that changes and modifications may be made within the scope of the appended claims without departing from the spirit 75 of the invention.

Referring more in detail to the figures of the drawing, a collar button of special and 80 novel form adapted to engage the usual buttonholes in a neck band 7 of a shirt and is 75 adapted also to retain a collar 8 in place thereon. For that purpose the collar button shown in Fig. 3 has spaced flanges 10 and 11 separated by a shank or neck portion 12 which in the preferred form is of noncircular cross 85 section. Formed on and preferably integral with the forward flange or head 10 of the collar button is a supplemental head 13 closely adjacent the forward flange 10 and spaced therefrom by a short shank or neck 90 portion 14, also preferably of non-circular cross section. Adapted to be resiliently forced over the head 13 is a co-operating member 15 directly attached to the central portion of the necktie 16 on its rear face. 95 This member 15 is preferably made of a small piece of flat resilient material having a non-circular opening 17 in its center and having bent up portions around the edges of this central opening. These edges are capable of 100 being forced over the supplemental head 13 and are adapted to resiliently engage the non-circular section of the short shank or neck portion 14.

In Fig. 4 a modified form of the invention 105 is shown in which the necktie 18 to be retained in position is provided with a small head 19 adapted to be attached to the rear face of the necktie 18 and having a shank portion similar to that adjacent the supplemental head 13 of the collar button shown in Fig. 3. This head 19 is adapted to engage a resilient co-operating portion 20 formed directly on and closely adjacent the front head 21 of the collar button shown in this figure.

110 It will be seen from the above description that with a necktie retained in position by

- the above described means its collar button will be prevented from angularly moving relatively to the collar band 7 of the shirt by reason of the non-circular cross section of the shank portion 12 of the collar button engaging the usual buttonholes formed in the collar band 7 and collar 8. Also due to the non-circular cross section of the shank 14 separating the supplemental head 13 from the front flange or head 10 of the collar button the co-operating member on the necktie 15 and the necktie 16 itself will be prevented from angularly moving relative to the collar button. With the parts in position therefore they will be held neatly and firmly together, so that the necktie 10 will always be maintained in its proper horizontal position and centrally disposed between the front opening of the collar 8.
- 20 What I claim is:
1. A tie retainer comprising in combination, a collar button having spaced flanges spaced apart by a shank portion non-circular in cross section and adapted to be engaged by a collar band so that said collar button is held against angular movement relative to said band, a tie, and interengaging head and socket means between the forward end of said collar button and rear face of said tie, one of which is resilient, the co-operating portions of said socket and collar button being non-circular in cross section and being resiliently engaged, whereby said tie is held against angular movement about said collar button.
  2. A tie retainer comprising in combination, a collar button having spaced flanges thereon, a shank between said flanges non-circular in cross section, a head formed on the forward face of one of said flanges and spaced therefrom by a short shank non-circular in cross section, and a tie having a socket attached thereto adapted to be resiliently forced over said head and engaging said short shank.

JOSEPH ROSMAN.
